COVER FOR GARMENT HANGERS

Filed Dec. 17, 1948

UNITED STATES PATENT OFFICE

2,539,621

COVER FOR GARMENT HANGERS

Homer E. Harmon, Arlington Heights, Ohio, assignor to The Fleischer Mills, Inc., Cincinnati, Ohio, a corporation of Ohio

Application December 17, 1948, Serial No. 65,922

4 Claims. (Cl. 223—98)

1

This invention relates to covers and more particularly to a soft flexible paper cover for triangular shaped garment hangers.

An object of the invention is to provide an inexpensive cover for a triangular shaped garment hanger which cover may be delivered to the user thereof in an assembled condition ready to receive a garment hanger inserted therein thru a side edge opening.

Another object of the invention is to provide a garment hanger cover from a single sheet of soft flexible paper foldable to provide a garment hanger receptive envelope, wherein said cover is characterized by the absence of foldable flaps as heretofore used in the formation of hanger receptive envelopes.

Still a further object of the invention is to provide a cover for a garment hanger comprising duplicate triangular shaped front and rear panels integrally connected along a side edge, the lower edges of which are permanently secured together in coplanar abutting relationship for providing an envelope opening along the other edge.

Still a further object of the invention is to provide a cover for a triangular shaped garment hanger which includes a closure or locking flap for positively securing a hanger interiorly of the cover.

Still a further object of the invention is to provide a cover for a garment hanger having the hereinabove described characteristics which may be inexpensively produced, folded and formed on a standard envelope machine, thereby eliminating the need for expensive, special machinery.

These and other objects are attained by the means hereinafter more fully described and as disclosed in the accompanying drawings, in which:

Fig. 1 is a plan view of a blank from which a cover embodying the teachings of the present invention may be fabricated.

Fig. 2 is an elevation of a completed, ready-to-use cover as sold to the user thereof ready for the insertion of a garment hanger therein.

Fig. 3 is a side elevation showing the cover of Fig. 2 applied to a garment hanger housed therein.

Fig. 4 is a sectional view on line 4—4 of Fig. 3.

Fig. 5 is a sectional view somewhat similar to Fig. 4 but wherein locking flap 20 overlappingly engages the outer face of the rear panel of the cover.

With reference now to Figs. 1 and 2, it will

2

be observed that the cover may be fabricated from a blank of soft flexible paper stock cut to provide a pair of substantially triangular shaped duplicate front and rear panels 10 and 12 interconnected along one side defined by fold line 14. Each panel includes a lower edge 16, side edges 14 and 18. It will be noted that side edge 18 of front panel 10 is defined by a fold line which sets off the closing or locking flap 10 20 from the panel.

It should be understood that the dimensional characteristics of panels 10 and 12 are such as to facilitate the formation of an envelope structure as disclosed in Figs. 2 and 3 adapted to 15 loosely receive a triangular garment hanger inserted endwise thereinto.

In fabricating the device for delivery to the user thereof, rear panel 12 may be folded about line 14 whereby to overlie front panel 10. The lower edges of panels 10 and 12 may be permanently secured together in coplanar abutting relationship as at 40 (Figs. 4 and 5) by means of a suitable adhesive which may, if desired, be suitably applied, by way of example, as at 22 20 along the bottom edge of panel 10. In this connection it should be clearly understood that adhesive strip 22 could just as well be applied along the lower edge of rear panel 12. It will be observed that when the lower edges of the front 25 and rear panels have thus been permanently secured together, the completed cover disclosed in Fig. 2 will be formed, said cover comprising a triangular shaped envelope permanently closed along bottom edge 16 and side edge 14, being open along the other side edge 18 whereby to accommodate a garment hanger inserted endwise therein.

When a hanger has been inserted into the triangular shaped envelope of Fig. 2, the upwardly inclined side legs 30 and 32 of the hanger will be disposed interiorly of side edges 14 and 18 of the cover and lower leg 34 positioned in spaced parallelism with lower edges 16, as disclosed in Fig. 3.

Flap 20 may be then folded over inclined leg 30 of the hanger and tucked or inserted downwardly between the adjacent inner faces of the inner and outer panels, as disclosed in Figs. 3 and 4. It will be observed that locking flap 20 45 thus completes the envelope around the hanger and secures the hanger within the envelope.

If desired, a spot 38 of suitable adhesive may be provided on lock flap 20 thereby facilitating permanent attachment of the locking tab 50 55 interiorly of the envelope whereby the envelope

cannot be removed from the hanger without destruction thereof. If desired, the nature of adhesive 38 may be of the so-called pressure-sensitive type or of that type which requires moistening in order to render effective its adhesive characteristics.

In some instances, lock flap 20 may be folded over inclined leg 30 of the hanger and thence folded downwardly in overlapping relationship with the outer face of rear panel 12, as disclosed in Fig. 5. It will be understood that lock flap 20 may be suitably secured to panel 12 by means of adhesive 38, or by any other suitable means, such as pinning, or the like. However, it should be understood that the cover will function quite satisfactorily even though flap 20 is not positively secured in closed or locked position illustrated in Figs. 4 and 5.

From the foregoing, it will be observed that I have provided a cover member for a garment hanger which may be inexpensively fabricated and which is particularly well adapted to be provided with printing completely covering the outer face of both the front and rear panels, wherein the exposed areas of said front and rear panels is not marred or interrupted by the presence of flaps, such as characterized by certain of the prior art devices, such as, by way of example, are disclosed in H. Taff Patent No. 2,072,243, dated March 16, 1937.

The cover while requiring but a minimum of stock provides an envelope or cover characterized by its utility, simplicity and effectiveness. The structural details of the device, tho simple, provides a cover which is extremely strong and dependable since the adjacent portions of the front and rear panels are integral, continuous and defined by fold line 14. When flap 20 is disposed in the closed or locked positions illustrated in Figs. 4 and 5, leg 30 of a hanger is likewise securely engaged.

The absence of an internal or external forming flap along side edge 14 greatly facilitates the ease with which hangers may be inserted endwise into the envelope cover of Fig. 2. My illustrated construction likewise enables the entire area of both front and rear panels to be fully utilized for advertising.

What is claimed is:

1. A cover for a garment hanger, comprising triangular shaped front and rear panels with one of the side edges common to both panels, means permanently securing said panels together along their respective bottom edges to form an envelope with one side edge and the bottom closed, the other side edge being open to accommodate a hanger inserted endwise, and a flap extending from the other side edge of one of the triangular panels adapted to be folded over the side edge of the other triangular panel to close said opening.

2. A cover for a garment hanger, comprising duplicate triangular shaped front and rear panels 10 with one of the legs of each of the triangles common to each other constructed and arranged to form an envelope open along one side to accommodate a hanger inserted endwise therein, and a closure flap secured to the other leg of one of 15 said panels adjacent said opening and adapted to be folded over the leg of the other panel to secure a hanger within said envelope.

3. A cover for a garment hanger, comprising triangular shaped front and rear panels each including bottom and side edges, with one of the side edges being common to both panels, means 20 permanently securing the bottom edges of said panels together in coplanar abutting relationship for forming an envelope open along one side, 25 a locking flap secured to the other side edge of one of said panels adjacent said open side and adapted to be folded over the side edge of the other panel to secure a hanger in said envelope.

4. A cover for a garment hanger, comprising a 30 triangular shaped panel having a bottom and upwardly convergent side edges, a triangular shaped second panel having a bottom and upwardly convergent side edges, one side edge of each panel being integral, a closure flap hinged 35 to the other side edge of said first panel adapted to be folded over the side edge of the second panel, and means permanently securing the bottom edges of said panels in coplanar abutting relationship for providing a triangular shaped hanger 40 receptive envelope open along one side edge.
